UNITED STATES PATENT OFFICE.

ALPHONSE FERNANDEZ, OF MOBILE, ALABAMA.

STREET AND STATION INDICATOR FOR CARS.

1,089,197.

Specification of Letters Patent.

Patented Mar. 3, 1914.

Application filed October 20, 1913. Serial No. 796,264.

To all whom it may concern:

Be it known that I, ALPHONSE FERNANDEZ, a citizen of the United States, residing at Mobile, in the county of Mobile and State 5 of Alabama, have invented certain new and useful Improvements in Street and Station Indicators for Cars, of which the following is a specification.

This invention relates particularly to apparatus for automatically indicating in succession the cross streets passed by a car while traveling its usual route, but my improvements may also be employed for indicating in succession the stations or points 15 of interest passed on the lines of other vehicles running on tracks.

The object of the invention is to provide simple and efficient mechanism which will automatically show to the occupants of a 20 car the name or designation of the cross streets which the car approaches, such mechanism being preferably put into operation when the car is in the middle of a block or midway between two cross streets.

25 In the accompanying drawings:—Figure 1 is a view, in vertical section, showing one form of my improved apparatus, certain parts being broken away. Fig. 2 shows a transverse section on the line 2—2 of Fig. 1, 30 looking in the direction of the arrows. Fig. 3 shows a transverse section on the line 3—3 of Fig. 1. Fig. 4 is a detail view in perspective, showing how the trolley wheel takes the current from a trolley wire for operating the apparatus when the latter is electrically operated. Figs. 5 and 6 are on an enlarged scale. Fig. 5 is a plan view of part 35 of the apparatus shown in Fig. 1 with the top of the casing removed. Fig. 6 shows a side elevation of such apparatus with the side of the casing removed. Fig. 7 is a detail view of the gearing employed for connecting the electric motor with the indicating devices. Fig. 8 is another detail view 40 of said gearing. Fig. 9 is a view, on an enlarged scale, of the apparatus shown in Fig. 1, but showing a certain addition thereto by means of which the apparatus may be mechanically operated. Fig. 10 is a view, in 45 side elevation, showing how the apparatus may be operated mechanically. Fig. 11 is a detail view of the mechanism employed for operating the web carrying the street names and numbers and indicating how this 50 web may be moved in opposite directions. Fig. 12 is a detail view, in section and on an

enlarged scale, showing the means for shifting the gearing whereby the indicating mechanism may be moved by the motor in opposite directions or may be thrown out of 60 operation.

My apparatus is especially intended for use on electrically propelled street cars operated by either overhead or underground trolleys, but it may be used on cars or vehicles of other kinds.

I will herein confine the description of my invention to apparatus especially suitable for use on street cars, said apparatus being propelled by electricity taken from 70 a trolley wire or by a suitable mechanical device on the track.

In Fig. 1 I have indicated a part of the car frame by the letter A and B designates the casing of the principal part of the indicator which may be placed at one end of the car in an elevated position so that its glazed opening b may be plainly seen. The end of the casing having the glazed opening b may be hinged at a so that the interior 80 of the apparatus may be conveniently reached. Within the casing, on a shaft c, is mounted an electric motor C which is at times supplied with current by wires d, one of which extends along or through the trolley pole D, and connects with a finger d' which is adapted to make wiping contact with an arm e extending from the trolley wire E. This arm is preferably located midway between two crossing streets so that current is only supplied to the motor for a 85 short time when the car has passed one street and is approaching another.

The shaft c is supported in a swinging frame I, comprising a horizontal cross-piece 95 i and the vertical arms i'. The frame also has a lateral extension i² to accommodate the motor, and to this extension is attached a handle I' which extends through an opening in the casing B and is provided with 100 notches i³ adapted to engage the casing in the manner indicated in Fig. 1.

The motor C is operatively connected with a large spur wheel F, by pinions G and H. One of these pinions is secured to the motor 105 shaft c while the other is supported on the outer end of an arm c' extending from the shaft c. The pinion H is secured to the shaft c (Fig. 5) and the pinion G at times meshes with the spur wheel F and then 110 operatively connects the shaft c with said spur wheel. The pin c² carrying the pinion

G, is extended through a curved slot b^2 in the casing and carries a nut or handle J' by means of which the pinion G may be moved to engage with the spur wheel F or to be disengaged therefrom. When the handle I' is in the position shown in Fig. 1 the motor is connected with the spur wheel F by both pinions G and H. If the pinion G is moved upward by the handle J' and 10 the handle I' is pushed inward the motor is connected with the spur wheel F by the pinion H only, and if the handle I' is drawn out to a sufficient extent the motor is entirely disconnected from the spur wheel. By this 15 mechanism the spur wheel may be made to revolve in either direction or may be so disconnected from the motor that the latter may operate without in any way affecting the indicator.

20 The spur wheel, when revolved, will have some momentum and in order to regulate this, I provide the brake mechanism K. This consists of an armature lever k pivoted at k' to the casing B and having a claw k^2 adapted to engage the spur wheel F. This 25 lever k is operated by an electro-magnet K' supplied with current by wires k^3 . Coöperating with the armature lever is a disk L, having a flat peripheral part l adapted to engage the lever k and connected with a pinion l' engaging the spur wheel F. When 30 the motor receives current motion is imparted to the spur wheel. The armature lever k is lifted and a complete revolution is given 35 to the disk L.

The contact devices d' and e engage each other for only a short time but long enough for the motor to be set in operation and the momentum of the motor is sufficient to 40 cause a proper operation of the spur wheel F which is moved far enough to cause the pinion l' to be given a complete revolution and also far enough to cause the web M to be shifted to change the name of the street 45 displayed. By giving to the pinion l' a complete revolution the disk L is revolved until its flat portion l comes under the armature lever k and as the circuit is now broken the armature lever drops and its 50 claw k^2 engages the spur wheel F and prevents further rotation thereof.

The names and numbers of the streets may be printed or indicated on a web M, attached at its opposite ends to rollers m, m', 55 and extending over guide rods N. The web may be made of great length sufficient to contain all the street names or numbers on the line, and may be passed from one roller to the other by the mechanism shown. The 60 rollers m, m' are located above and below the glazed opening b so that the part of the web between the rollers may display the name or number of the street as it is approached. The roller m is carried by two levers N⁴, 65 pivoted to the opposite side of the casing at

n. The roller m extends through curved slots b^4 in the sides of the casing and carries heads or handles N' whereby the roller may be shifted. These heads or handles may be threaded nuts so as to hold the roller in its 70 adjusted position. The roller m carries a pinion O, engaging or adapted to engage the spur wheel F, and by means of the handles N' the pinion O may be engaged with or disengaged from said spur wheel. Similarly the roller m' is connected with the outer ends of levers N² pivoted at n² to the casing B and the ends of the roller m' extend through guide slots b^5 in the casing and are provided with handles N³ by means 80 of which the pinion O' carried by the roller m' may be engaged with or disengaged from the spur wheel F. The handles N³ are also preferably in the form of screw nuts by means of which the roller m' may be held 85 in its adjusted position. In this way the web M may be drawn from the roller m onto the roller m' or vice versa, by means of the gearing above described.

In Fig. 1 the apparatus is shown as adjusted to cause the web to pass from the roller m' to the roller m, but after the web is wound on the roller m it may, if desired, be wound by hand back onto the roller m', but the mechanism shown provides means by 95 which the motor C may be employed for this purpose at any time, or it may do so step by step as the car returns over the route previously traveled.

By employing the pinions G and H the 100 spur wheel F may be revolved in either direction and by shifting the pinions O and O' complete control is given to the movement of the web under all conditions.

It may be desirable to display the names 105 or numbers of the streets at both ends of the car, or it may be desirable to have the motor operate signs or apparatus for not only displaying the street names or numbers but also advertisements, and when this is 110 the case I employ another indicator P, illustrated in Fig. 1. The casing Q of this part of the apparatus may be of any suitable kind and it is provided with a glazed opening q. Within the casing is a large spur 115 wheel F' pivotally connected with the sides of the casing at f and geared to the spur wheel F by a shaft F², carrying at opposite ends pinions f², f³ geared as shown with the spur wheels F, F'. 120

The web M' having the street numbers and names on it is connected with rollers R, R' mounted on levers r, pivoted at r' to the sides of the casing. The rollers R, R' extend through curved slots r² in the casing 125 and carry nuts R² similar to the nuts N' by means of which the levers may be shifted so that either the roller R or R' may be operatively connected with the spur wheel F' by its pinion r³. It will thus be understood 130

that every time the car reaches the middle of the block the apparatus is operated to shift the web M or both webs M , M' to display the name or number of the next street or 5 any other desired designation.

I may so construct the apparatus that it may be operated either electrically or mechanically. Thus in Fig. 9 I have shown mechanism the same in all respects as that 10 shown in the preceding figures of the drawings, but being provided with additional devices by means of which the apparatus may be connected with mechanical means for operating it. As most of the mechanism is 15 similar to that shown in Fig. 1 similar letters of reference have been employed in Fig. 9. The shaft c , as shown in Fig. 9, is provided with a spur wheel S carrying a sprocket chain S' extending through openings s in the bottom of the casing B and this chain extends also downwardly through the floor T of the car, as shown in Fig. 10, its lower portion passing around a sprocket wheel U the shaft u of which is suspended 20 by a hanger t , depending from the car floor. The hanger t also supports at its lower end a horizontally arranged bar V , from which depends a bracket v to which is jointed at v' the upper end of a bar V' , carrying at its 25 lower end a roller V^2 . To this bar V' is attached a horizontal frame W , connected by springs w to the horizontal bar V . The arrangement is such that the bar V' may swing on its pivot v' and thus swing the 30 frame W . To the opposite ends of this frame W are pivoted at w' pawls X , X' . These extend up through the horizontal bar V and are adapted to engage a ratchet wheel X^2 , secured to the shaft u . 35

40 Each pawl carries at its upper end a tooth y which is pivoted to the pawl at z . A spring z' is interposed between the tooth and the outer portion of the pawl. The teeth y are adapted to engage the teeth of the ratchet wheel X^2 while the upper portions z^2 of the pawls are adapted to engage rollers y' carried by hangers t' extending diagonally downward and inward from the floor of the car. By these devices the pawls 45 are guided in such manner that when one of them is raised its upper portion z^2 , which is engaged by the roller y' , will cause the teeth y to engage the ratchet wheel X^2 and move it and when the pawl descends its tooth y will be moved out of the path of the 50 ratchet wheel. By reason of the spring z' the tooth may yield when retreating from the ratchet wheel.

Y indicates a bell crank lever pivotally 60 connected with the bar V and having one arm connected by a rod Y' with a hand lever Y^2 . The other arm of the lever Y is connected by a rod Y^3 with the bar V' by a slot-and-pin connection y^2 . By means of the lever Y^2 the roller V^2 may be raised and low-

ered so as to be placed into or out of operating position.

Z indicates a ramp rail or other projection on the track which is adapted to engage the roller V^2 . This device is preferably located 70 on the track midway between two cross streets and when the roller V^2 engages it the bar V' will be swung on its pivot and cause one of the pawls to be operated to turn the shaft u and thus the sprocket chain 75 S' and then by means of the sprocket wheel S the motor shaft c , and so the indicator will be properly operated. It will be observed that the wheel X^2 is considerably larger than the wheel S and a partial revolution of 80 the wheel X^2 may impart a complete revolution of the wheel S . The gearing may of course be properly constructed and arranged to accomplish the desired result.

It will be understood that the mechanism shown in Fig. 1 may be used separately and independently of that shown in Figs. 9 and 10. At times the electric motor may be disregarded and the apparatus 85 operated by purely mechanical devices. In 90 either case the desired result will be obtained.

It will also be understood that the operation of one form of the apparatus does not interfere with the operation of the other 95 form thereof. Thus the apparatus shown in Fig. 9 may be electrically operated if the car is on an electric line where it is desired to employ the electric motor for operating the indicator. If the motor is thus operated 100 the sprocket chain will be turned because the pawls X , X' are out of the path of the ratchet wheel X^2 and no harm can result from the operation of the sprocket chain. In like manner if the apparatus is operated 105 mechanically the presence of the electric motor is never a disadvantage, but where the apparatus is operated mechanically the brake mechanism K will not be employed.

I claim as my invention:

1. A street and station indicator, comprising rollers, a web attached to said rollers and carrying the street and station numbers, a spur wheel, gearing for connecting said spur wheel with said rollers, an 110 electric motor, gearing connecting the motor with the spur wheel, means for shifting the gearing to reverse the movement of the spur wheel, and brake mechanism for the spur wheel comprising an electrically operated armature lever engaging said spur wheel and a disk having a flat side revolved by said spur wheel and engaging said armature lever.

2. A street and station indicator, comprising a web containing designations of the streets and stations, rollers to which the opposite ends of the web are connected, a spur wheel, gearing for connecting the spur wheel with said rollers, means for connect-

110

115

120

125

130

ing and disconnecting said gearing from said spur wheel, an electric motor, pinions for connecting said motor with the spur wheel, means for shifting said pinions to reverse the movement of said spur wheel and electric brake mechanism operating upon said spur wheel.

3. A street and station indicator, comprising a web containing designations of 10 the streets and stations, rollers to which the opposite ends of the web are connected, a spur wheel, gearing between said rollers and said spur wheel, a shaft (c), means for rotating said shaft, a pinion on said shaft, an 15 intermediate pinion meshing with the pin-

ion on said shaft and with the spur wheel, means for moving said intermediate pinion into and out of gear with said spur wheel, means for moving the pinion on said shaft into and out of gear with said spur wheel, 20 and means for shifting the gearing between said web-carrying rollers and said spur wheel into and out of communication with said spur wheel.

In testimony whereof I have hereunto 25 subscribed my name.

ALPHONSE FERNANDEZ.
